EXPENDABLE CONCRETE FORM MEMBER

Michael H. Barrett, Westminster, and Charles D. Keyes, Denver, Colo., and James T. Ream, San Francisco, Calif., assignors to Ketchum, Konkel, Barrett, Nickel and Austin, Inc., Denver, Colo., a corporation of Colorado

Filed Nov. 8, 1968, Ser. No. 14,371

Term of patent 14 years

Int. Cl. D25—01
U.S. Cl. D13—1

FIGURE 1 is a perspective view of the upper surface of an expendable concrete form member showing our new design, said view looking from the two column supported corners to the third corner;

FIGURE 2 is a perspective view of the lower surface of the expendable concrete form member shown in FIGURE 1, said view looking from the third corner to the two column supported corners;

FIGURE 3 is a bottom plan view of the expendable concrete form member shown in FIGURE 2;

FIGURE 4 is an elevational view of the expendable concrete form member taken along line 4—4 of FIGURE 3, the dotted lines showing columns upon which said member may be supported; and

FIGURE 5 is an elevational view of the expendable concrete form member taken along line 5—5 of FIGURE 3, the dotted lines showing columns upon which said member may be supported.

The dotted lines in FIGS. 4 and 5 are disclosed for illustrative purposes only and form no part of the claimed design.

We claim:

The ornamental design for an expendable concrete form member, as shown and described,
